[57] CLAIM

The ornamental design for a simulation shooting game machine, as shown and described.

DESCRIPTION

FIG. 1 is a front view of a simulation shooting game machine showing my new design;

FIG. 2 is a rear view thereof;

FIG. 3 is a top view thereof;

FIG. 4 is a bottom view thereof;

FIG. 5 is a right side view thereof; and,

FIG. 6 is a left side view thereof.
